Primary Examiner — Kevin K Rudzinski*Assistant Examiner* — Evans David Delesline(74) *Attorney, Agent, or Firm* — Wilson Sonsini Goodrich & Rosati(57) **CLAIM**

The ornamental design for a necklace, as shown and described.

DESCRIPTION

FIG. 1 is a bottom front right perspective detail view of a necklace, showing my new design;

FIG. 2 is a bottom rear right perspective detail view thereof;

FIG. 3 is a bottom front left perspective view thereof;

FIG. 4 is a top front left perspective detail view thereof; and,

FIG. 5 is a front elevational view thereof.

The broken lines shown in the drawings represent portions of the necklace that form no part of the claimed design.
